WALDO E. PULLARD, OF CUMBERLAND, MARYLAND.

BAGGAGE-CHECK PROTECTOR.

1,213,007.

Specification of Letters Patent. Patented Jan. 16, 1917.

Application filed June 3, 1916. Serial No. 101,578.

To all whom it may concern:

Be it known that I, WALDO E. PULLARD, a citizen of the United States, and a resident of Cumberland, in the county of Allegany and State of Maryland, have invented 5 a certain new and useful Improvement in Baggage-Check Protectors, of which the following is a specification.

My present invention relates generally to 10 devices for attachment to trunks and other baggage, for the purpose of holding baggage checks thereon, particularly in lieu of the usual string or cord fasteners for such checks, my object being to provide a device 15 attachable to a trunk for holding baggage checks in such manner as to prevent removal of the baggage check, without mutilation, and the substitution of another check therefor.

20 In the accompanying drawings which illustrate my present invention, Figure 1 is a perspective view of a trunk illustrating the practical application of my invention; Fig. 2 is a plan view of my improved baggage check protector, with a check locked therein, and with the cover plate of the locking mechanism removed; Fig. 3 is a similar view showing the same part in released position, either preparatory to locking the bag- 25 gage check therein, or preparatory to its removal; Fig. 4 is a plan view of one end portion of the protector, illustrating the cover plate of the locking mechanism in position; Fig. 5 is a longitudinal section 30 taken through the protector substantially on line 5—5 of Fig. 2; Fig. 6 is a similar view taken therethrough substantially on line 6—6 of Fig. 3; Fig. 7 is a transverse section taken therethrough on line 7—7 of 35 Fig. 2; Fig. 8 is a similar view taken therethrough substantially on line 8—8 of Fig. 2; Fig. 9 is another similar view taken therethrough substantially on line 9—9 of Fig. 2; Fig. 10 is a perspective view illustrating 40 the connection for raising one end of the baggage check preparatory to its removal, detached; Fig. 11 is a similar view of the releasing bar; Fig. 12 is a similar view of the cover slide; Fig. 13 is a similar view, 45 partly broken away, illustrating the bearings for the locking bolt, and Fig. 14 is a perspective view illustrating the key for releasing the lock, with its numbered check receiving clip corresponding to the number 50 upon the cover plate of the locking mechanism, as shown in Fig. 4.

Referring now to these figures, I provide a baggage check protector which is attachable at any suitable point upon a trunk, such for instance as indicated at A in Fig. 1, being preferably disposed upon and connected to, one end of the trunk beneath one of the handles A' thereof, as will be plainly seen by reference to this figure.

The main frame of my improved protector includes a base plate B, the said base plate being generally rectangular in form and having side flanges B', provided with inturned and downwardly bent extensions along the major portion of the length of 55 the said base plate whereby to form guides B² for a purpose to be hereinafter described. This base plate B has longitudinally extending central slots b and b' adjacent its opposite ends, the slot b extending through the 60 respective end of the said plate, while the slot b' extends only to its respective end of the plate as will be seen by reference to Fig. 6 in particular, this end of the plate being provided with an upwardly and in- 65 wardly bent flange B³, having a central ex- 70 tension b² overlying the slot b' in spaced relation and provided with an inner down- turned edge b³ for a purpose to be herein- 75 after described.

The longitudinal slots b and b' form the 80 end portions of a guide channel, the central portion of which is formed by an inset por- 85 tion B⁴ of the base plate B connecting the 90 said slots b and b', the complete channel 95 thus formed being for the reception of a slide plate C, of somewhat less length than the base plate B, the outer end of which has an upturned flange C', forming a handle 100 and disposed within the slot b as will be clearly seen by reference to Figs. 2 and 3, the inner end of the slide plate C having a central upstanding pin C² upon which the eyelet D' of a baggage check D may be conveniently received, the body of said check 105 being movable endwise upon the base plate B, below a slide, which consists of side bars E disposed within the guide flanges B² before mentioned, as will be clearly seen by reference to Figs. 5 and 8, and cross bars E' and 110 E² connecting the side bars E, this slide preventing removal of the baggage check, and being movable at all times, in order that all printed or written matter upon the face of the baggage check may be readily seen and 115 read. The slide C being thus movable in the channel of the base plate, flush with the

lower surface of said base plate, is prevented from removal, by transversely extending straps F and F', which are securely fastened in any suitable manner across the lower surface of the said base plate B and which are provided with extending portions having apertures f by which the entire device may be secured, with suitable fastening members, to the trunk in connection with which it is to be used.

Mounted transversely across, and above, the slot b' of the base plate B, is a shield G, the ends of which are provided with laterally projecting rods G' having their extremities journaled in portions of the side flanges D' as clearly seen by reference to Fig. 7, this shield G having a slot g which receives the upstanding pin C² of the locking slide C, when the latter is at the limit of its inward movement, and which in such position carries the baggage check disposed thereon, to the locked position as shown in Fig. 2.

Adjacent the opposite end of the main frame, a lock casing H is formed, between the adjacent portions of the side flanges B' and between transverse bars H' and H², connecting such side flanges, and against which transverse bar H², the handle portion C' of the locking slide C abuts in the inner locked position, as clearly seen by reference to Figs. 2 and 5, this transverse bar being provided with a recess h, and with rigid tubular bearings h' and h² upon opposite sides of its recess for a locking bolt I. The said handle portion C' of the locking slide C is also provided with an inwardly projecting rigid tubular bearing piece C³ which is movable to a position along with and between the bearings h' and h², so that when in such position it may receive the locking bolt I therethrough as will be clearly seen by reference to Figs. 2 and 9. The locking bolt I also passes through a bearing h³ upon the bar H² and is controlled by a spring i. This locking bar is also provided with a laterally projecting key engaging member i' which the key J, as shown particularly in Fig. 14, engages and moves in order to withdraw the bolt from the keeper C³ of the locking slide.

Disposed between the transverse bar H² and the handle portion C' of the locking slide I, is a presser bar K, having inwardly projecting guide rods K' adjacent its outer end, which are slidably mounted through guide apertures in the transverse bars H² and H' before mentioned, these guide rods K' being also provided with springs K² coiled therearound, normally tending to force the presser bar K away from the transverse bar H². Thus when the lock is released in the manner before described, the presser bar at once forces the locking slide rearwardly from the locked position as

shown in Fig. 2, to the released position as shown in Fig. 3, these positions being respectively shown in Figs. 5 and 6.

Pivotedly mounted upon a rod L', extending transversely across one end of the inset portion B' of the base plate B, adjacent its slot b', the downturned ends l of which rod are fixed into the base plate as shown in Fig. 8, is a slotted lifting plate L, into the slot of which the pin C² moves when the parts are in released position as shown in Fig. 3, the free end of this lifting plate L extending above the intermediate crank portion M, of a transversely extending rod, the ends m of which are journaled in the side flanges B', one end l having an angular extension m' projecting parallel with, and along the outer side of one of the flanges B', as particularly seen in Figs. 2 and 3, at a point within a recessed portion of the respective side flange. This recessed portion is shown at b², and provides for the reception of a lever N, one end of which lever N is pivotally connected to the flange at n, and the opposite end of which receives the said extension m' so that by pressing downwardly upon the free end of the lever N, the crank portion M of the cross rod may be raised, thus raising the plate L which rests thereon, in order to lift the eyelet end of the baggage check off of the pin C², as clearly seen in Fig. 6, in order to facilitate its removal.

It will be noticed particularly by reference to Figs. 2 and 3, that the shield G which receives the pin C² in its slot g, in the locked position of the parts, and thus prevents the eyelet end of the baggage check D from being lifted off of this pin, is disposed adjacent to, but out of contact with, the extension b² of the flange pin B² of the base plate B, the particular relation between these parts permitting slight rotative movement of the shield G, by virtue of its journaled extending rod G', in order that the eyelet end of the baggage check may be thrust thereunder when the slide C is forced inwardly to locked position.

The lock casing H is covered by a plate H³ as shown in Fig. 4, having a key slot h⁴, and also having a number plate H⁴, the number of which is to correspond with the number plate J' flexibly attached to the key J of the particular protector, this number plate J' of the key being preferably provided with a clip J² connected therewith, to receive the detached portion of the baggage check, which is separated therefrom as is usual, when the check is made out, the owner of the particular baggage retaining the key and the detached portion of the check which may be held in the clip J², when the baggage man, porter, or other attendant, places the body portion of the bag-

gage check as shown at D in the several figures, within the baggage check protector.

In placing the body of the baggage check D within the protector, it is inserted endwise beneath the transverse rod E' of the slide, and moved longitudinally beneath the rod E² to a sufficient extent to permit its eyelet D' to be disposed on the pin C² when the parts are in the position shown in Fig. 3. If the baggage check is of considerable length, its end may freely extend upwardly and outwardly over the cover plate H² of the lock casing, and may be guided upwardly over such cover plate by means of guide strips B², inclined upwardly from the base plate B adjacent the transverse bar H' as clearly seen by reference to Figs. 2 and 6, these guide pieces being formed by struck-up portions of the base plate B if it is so desired.

With the baggage check in the position shown in Fig. 3, the handle end of the locking slide C is grasped, and moved inwardly, carrying the presser bar K inward with it, until its bearings C³ extend into alined position with the bearings h' and h², at which time the release of the key J from its position shown in Fig. 3, permits the locking bolt I to move under the action of its spring into locked position, and through the bearing C³ as shown in Figs. 2 and 9. In the locked position, thus attained, the eyelet end of the baggage check extends beneath the shield G as will be seen by reference to Fig. 2, and the pin C² moves into the slot g of such shield, so that thereafter, and during the time the parts are in the locked position, the baggage check is prevented from removal without mutilation of its eyelet end. Thus all substitution of baggage checks is effectively prevented, and baggage thievery effectively stopped.

When removing the baggage check, the key J is inserted and turned from the position shown in Fig. 2 to the position shown in Fig. 3, withdrawing the locking bolt I, and permitting the presser plate K to force the slide C outwardly the instant it is released. The parts will then again be in the position shown in Fig. 3, and upon simple pressure upon the lever N, the lifting plate L may be raised, carrying the eyelet end of the baggage check with it, as shown in Fig. 6, so that this end of the check may be readily grasped, and the check drawn lengthwise out of the protector, in substantially the same manner it is inserted therein in the first instance.

I claim:—

1. In a baggage check protector, the combination of a main frame, a locking slide movable in the frame and carrying an upstanding pin on which the eyelet of a baggage check may be disposed, a shield carried by the frame and into which the said

pin is movable in the locked position of the slide, and locking means for securing the slide in locked position.

2. In a baggage check protector, the combination of a main frame, a locking slide 70 movable in the frame and carrying an upstanding pin on which the eyelet of a baggage check may be disposed, a shield mounted in the frame above the slide, and having a slot into which the said pin of the slide is 75 movable in the locked position, said shield also having a limited rotary movement to permit the baggage check to be effectively guided thereunder, and locking means for securing the slide in locked position. 80

3. In a baggage check protector, the combination of a frame, a slide movable in the frame and having a baggage check engaging portion, a shield carried by the frame and beneath which said engaging portion of 85 the slide is movable to locked position, and means for locking the slide.

4. In a baggage check protector, the combination of a main frame, a slide movable in the frame and having a baggage check 90 engaging portion, a shield carried by the frame and beneath which said engaging portion of the slide is movable to locked position, means for locking the slide, and a slide frame adjustable in the main frame 95 and adapted to receive the baggage check thereunder.

5. In a baggage check protector, the combination of a main frame including a base plate having side flanges, a locking slide 100 having guided movement in the base plate to and from locked position, and provided with an upstanding pin on which the eyelet of the baggage check may be disposed, means for locking the slide, and a shield carried by the frame and having a lower slot 105 into which the said pin is projected when the slide is moved to locked position, said shield having a limited rotary movement with respect to the slide and the main 110 frame, and receiving the engaged portion of the baggage check thereunder.

6. In a baggage check protector, the combination of a main frame including a base plate having side flanges, a locking slide 115 having guided movement in the base plate to and from locked position and provided with an upstanding pin on which the eyelet of a baggage check may be disposed, means for locking the slide, a shield carried by the frame and having a lower slot 120 into which the said pin is moved to carry the engaged portion of the baggage check beneath the shield, and a slide frame superposed on the base plate and slidable thereon, said frame including transverse bars beneath which the body of the baggage check may be disposed. 125

7. In a baggage check protector, the combination of a frame, a slide movable in the 130

frame and having an upstanding pin upon which the eyelet of a baggage check may be disposed, a shield carried by the frame and beneath which said pin is movable with the slide to locked position, and means for lifting the eyelet portion of the baggage check from the said pin when the slide is released and moved from the shield, said means comprising a plate pivoted in the frame beneath the baggage check, a rod extending transversely through the frame and having a crank portion beneath the said plate, and

a lever pivoted on the frame and engaging a portion of the said rod whereby to rotate the same and raise its crank portion and the 15 said lifting plate, thus forcing the eyelet portion of the baggage check upwardly off of the engaging pin, all substantially as described.
